UNITED STATES PATENT OFFICE.

HARRY A. KOENIG, OF PHILADELPHIA, PENNSYLVANIA.

FUEL ECONOMIZER.

Application filed January 8, 1921. Serial No. 435,841.

To all whom it may concern:

Be it known that I, HARRY A. KOENIG, a citizen of the United States, and a resident of the city of Philadelphia, county of Philadelphia, State of Pennsylvania, have invented certain new and useful Improvements in Fuel Economizers, of which the following is a specification.

Some of the objects of the present invention are to provide a means for effecting a more complete combustion in stoves, boilers, furnaces, or any other heaters; to provide a device arranged to operate in conjunction with a combustion chamber to retard and 15 ignite waste gases from the fire; to provide an air supply device for a combustion chamber whereby a relatively cool body of air is distributed above the fire bed; to provide an air supply means for a combustion chamber whereby the quantity of air can be proportioned in accordance with conditions 20 within the combustion chamber; to provide an air supply means for a combustion chamber whereby entering air is evenly distributed by a plurality of jets; and to provide other improvements as will hereinafter appear.

In the accompanying drawings, Fig. 1 represents a horizontal section on line 1—1 30 of Fig. 2 of a furnace showing one form of the present invention in operative position within the combustion chamber; Fig. 2 represents a vertical section on line 2—2 of Fig. 1; Fig. 3 represents a longitudinal section of the fuel economizer body; and Fig. 35

4 represents a section on line 4—4 of Fig. 3.

Referring to the drawings, one form of the present invention comprises a body 10 arranged to be rigidly fastened to a furnace 40 or heater door 11 in a manner to project within the combustion chamber 12 in relatively close proximity to the bed of coal or other combustible.

For securing the body 10 to the door 11 45 for axial adjustment, so that the body 10 can be properly located with respect to the center of the combustion chamber 12, the body 10 is provided with a threaded stem 13 arranged to pass freely through an opening 14 formed in the door 11. This stem 13 carries a pair of washers 15 and a pair of nuts 16, one washer 15 and one nut 16 being at one side of the door 11 and the other washer 15 and nut 16 being at the opposite 50 side of the door 11, washers 15 in each instance being between the respective nuts 16

and the door 11. Thus, with the proper projection of the body 10 having been determined, the nuts 16 are fed towards each other to rigidly clamp the washers 15 60 against the door 11. The opening 14 in the door 11 is preferably located toward the hinge side of the door in order to insure the body 10 swinging clear of the door frame when the door is opened to replenish the fire 65 or for any other purpose. Also the opening 14 in the door 11 is located a suitable distance from the lower edge of the door 11 so that the discharge end of the body 10 is 70 properly located with respect to the fuel 75 bed.

As a means for admitting air to the combustion chamber, the body 10 has a longitudinally disposed channel 20 which extends through the stem 13 and has communication 80 with the outside air by way of radial ports 21 formed in a cap 22 which has threaded engagement with the end of the stem 13. This cap 22 may be fed relative to the stem 13 so that the end of the latter acts as a 85 valve to adjust the size of the ports 21 to regulate the amount of air passing to the combustion chamber by way of the body 10. A relatively small port 23 traverses the end wall of the cap 22 to insure some air always 90 entering the body 10, in case the ports 21 should become entirely closed through inadvertence or otherwise. A wing set screw 24 or other fastening device serves to fit the cap 22 in adjusted position upon the stem 13.

In order to distribute the air entering the combustion chamber, the body 10 terminates at its inner end in a head 25 forming an internal chamber 26 which receives the air from the channel 20. This head 25, while preferably flat on two opposite side faces, has a curved inner face 27 which forms a laterally extending nose 28, the opposite side 95 of which gradually tapers toward the body portion and merges into the wall of the body 10, thereby providing for the gradual expansion of the air entering the chamber 26.

The inner face 27 of the distributor head 25 is provided with outlets 30, preferably all in the same horizontal plane and so spaced as to divide the discharged air into a plurality of jets which spread the air over the central portion of the combustion chamber. This distribution of the air takes place 100 evenly over the rising gases by the provision of a baffle 31 within the chamber 26 and ex- 110

tending transversely of the path of the entering air. Also it terminates at each end a relatively short distance from the wall of the heads 25 so that two portions of the entering air pass around the baffle 31 while the remaining portion is deflected over the baffle to the row of end openings. The arrangement of the baffle 31 is such as to so proportion the body of entering air that 10 each jet delivers the same quantity of air.

The construction of the present invention differs from those heretofore employed in that the temperature of the entering air is maintained relatively low, due in part to 15 the expansion within the chamber 26 and in part to the fact that only a small portion of the body 10 is exposed to the heat of the fire. As a result the air delivered is relatively cool and therefore follows a downward path 20 within the combustion chamber, acting in a measure as a blanket which retards the rising gases. These gases which otherwise would escape to the flue, are ignited by the oxygen from the fresh entering air and a 25 more complete combustion takes place. In those devices where the entering air is pre-heated to a relatively high temperature, the gases rising within the combustion chamber are accelerated as they meet the heated air 30 and any increased combustion takes place in the flue or the passages adjacent thereto instead of at a point in the chamber where the heat units are available for heating purposes.

35 In the present invention the flue damper can be adjusted to nearly a closed position to further retard the gases and with the air

inlet ports 21 adjusted in accordance with the siphoning action at the distributor outlets 30, a condition is reached where substantially all the gases are consumed and all 40 available units utilized.

Although only a single form is shown in which this invention may be embodied, it is to be understood that the invention is not 45 limited to any specific construction, but might be applied in various forms without departing from the spirit of the invention or the scope of the appended claim.

Having thus described my invention, I 50 claim:

55 In a fuel economizer, a body arranged to project within the combustion chamber of the heater, said body comprising an elongated portion forming an inlet conduit and a head attached to said portion extending laterally to one side only with respect thereto and forming a chamber converging toward the outer end of said head, said head having a convex discharge face provided with a plurality of outlets, a vertically disposed baffle extending in close proximity to said discharge face and spaced from one side of said head, said baffle being in the path of the entering air, a pipe connected to said body portion and communicating with the conduit therein, means for connecting said pipe to the door of said heater, and controlling means for admitting air to said pipe.

60 Signed at Philadelphia, in the county of Philadelphia, State of Pennsylvania, this 28th day of December, 1920.

65 HARRY A. KOENIG.
